United States Patent Office.

GEORGE F. PERKINS AND S. F. GIBBS, OF HOLYOKE, MASSACHUSETTS.

Letters Patent No. 77,651, dated May 5, 1868; antedated April 28, 1868.

IMPROVED DOOR-FASTENER.

The Schedule referred to in these Letters Patent and making part of the same.

TO ALL WHOM IT MAY CONCERN:

Be it known that we, GEORGE F. PERKINS and S. F. GIBBS, both of Holyoke, in the county of Hampden, and Commonwealth of Massachusetts, have invented a new and useful Adjustable Door-Fastener and Match-Safe; and we do hereby declare that the following is a full, clear, and exact description thereof, reference being had to the accompanying drawings, making a part of this specification, and to the letters of reference marked thereon, in which—

Figure 1 is a side view of our invention.

Figure 2 is a side view with the cover removed.

Figure 3 is an end view of the fastener with the cover removed.

Figure 4 is a horizontal section through line E F of fig. 2; and

Figure 5 is a side view of the catch.

The nature of our invention consists in constructing a catch, with a screw-thread cut upon one end, to operate in a case, one part of said case serving as a nut to turn upon said catch, in such manner that it will be adjustable to secure or fasten doors of different thicknesses; and so arranging said case and catch with a cover that it may be easily and conveniently carried in the pocket, to be used when required, said case furnishing sufficient space to also serve the purpose of a pocket match-box.

To enable others skilled in the art to make and use our invention, we will proceed to describe its construction and mode of operation.

In the drawings, B is the case, which may be cylindrical in form, having at one end, h, the nut b attached, through which, in its centre, is a hole, g, having a female screw-thread cut in it.

The bar C is made flat, having, at one end, the catch or projection d, the other end of the bar C being made round, and having the male screw-thread, e, cut upon it, which is made to fit and works in, the female screw-thread cut in the hole g. Upon the inside of the case B is the slight projection or shoulder a, which serves as a stop for the end of the cover A when it is inserted in the case B.

The case B may have the ornamented annular projection i, to give the case B additional strength; and the end, h, of the case B, and also the nut b may be ornamented with any desirable device to add to its appearance. The catch d may be made sharp at the end, to facilitate its entrance into the wood of the door-frame when there is no mortise into which to insert it.

Having thus described its construction, we will proceed to describe its operation.

The case B having been first removed from the rod C, or withdrawn from the catch d a sufficient distance, the door to be secured is slightly opened, and the catch, d, inserted in the socket or mortise of the door-catch, and the door is then shut, leaving the catch d in the mortise, and the bar C projecting between the door and its frame, upon the inside, and the case B is then screwed on to the bar C, until the end, h, of the case B comes against the door. This fastens the door firmly and securely, so that it cannot be opened from the outside.

By making the case in this way, sufficient space is afforded in said case to serve as a receptacle for matches, when desirable, and by varying the size and form of said case, a convenient match-box of any capacity is readily secured.

Our invention is cheap in its manufacture, is free from complication, presents no sharp angles to wear the pocket in carrying it, and is adapted for use both as a portable match-box, and in fastening doors of different thicknesses, as it is adjustable in its operation.

We are aware that various devices have been used for this purpose of fastening doors, as in Letters Patent granted to J. B. Frazer, dated September 30, 1862, and numbered 36,563; and also in Letters Patent granted to L. C. Bignall, dated May 31, 1864, and numbered 42,924; but our invention differs from said devices very materially, and we disclaim any and every part of said devices, irrespective of our construction and arrangement; but, having described our invention,

What we claim as new, and desire to secure by Letters Patent, is—

A combined adjustable door-fastener and match-safe, consisting of the case B, cover A, and bar C, the whole constructed and operating substantially as described.

Witness our hands, this 25th day of July, 1867.

GEORGE F. PERKINS,
S. F. GIBBS.
